(57) **CLAIM**

The ornamental design for a filter for a deep fryer, as shown and described.

DESCRIPTION

Figure 1.1 is a perspective view of a filter for a deep fryer in accordance with a first embodiment showing my new design;

Figure 1.2 is a front elevation view thereof;

Figure 1.3 is a rear elevation view thereof;

Figure 1.4 is a left-side elevation view thereof;

Figure 1.5 is a right-side elevation view thereof;

Figure 1.6 is a top plan view thereof;

Figure 1.7 is a bottom plan view thereof;

Figure 1.8 is a perspective view thereof, in an extended configuration;

Figure 2.1 is a perspective view of a filter for a deep fryer in accordance with a second embodiment;

Figure 2.2 is a front elevation view thereof;

Figure 2.3 is a rear elevation view thereof;

Figure 2.4 is a left-side elevation view thereof;

Figure 2.5 is a right-side elevation view thereof;

Figure 2.6 is a top plan view thereof;

Figure 2.7 is a bottom plan view thereof; and,

Figure 2.8 is a perspective view thereof, in an extended configuration.

The filter for deep fryer includes a symbolic break along its length drawn in broken lines. The area between the break lines forms no part of the claimed design. The broken lines and the areas within them depict portions of the filter for deep fryer that form no part of the claimed design.
